J. A. AXT,
GRAIN BOARD HOLDER,
APPLICATION FILED OCT. 7, 1919.

1,391,292.

Patented Sept. 20, 1921.

UNITED STATES PATENT OFFICE.

JOSEPH AMY AXT, OF AMBOY, MINNESOTA.

GRAIN-BOARD HOLDER.

1,391,292.

Specification of Letters Patent. Patented Sept. 20, 1921.

Application filed October 7, 1919. Serial No. 329,068.

To all whom it may concern:

Be it known that I, JOSEPH A. Axt, a citizen of the United States, residing at Amboy, in the county of Blue Earth and State of Minnesota, have invented a new and useful Grain-Board Holder, of which the following is a specification.

This invention contemplates the provision of improved means for holding the door boards in position in a grain car.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed without departing from the spirit of the invention.

In the accompanying drawings:

Figure 1 is a vertical sectional view of a grain car equipped with my improved grain door and board holder.

Fig. 2 is a horizontal sectional view, and

Fig. 3 is a transverse fragmentary sectional view on the line 3—3 of Fig. 1.

Fig. 4 is a perspective view showing one of the levers.

The numeral 10 designates a car having a floor 11 and a ceiling 12. The door opening is designated at 72 and at each side of the door opening are arranged the door posts 14.

Instead of nailing the boards 15 to the posts or frame 14, there is provided at the inner face of one door-post a vertical shaft 16 having an obtuse angular clamping jaw 17 rigid therewith and extending the entire height of the opening 72, the upper end of the shaft being pivotally suspended from the top of the car by means of a hanger 18, so that the shaft can swing in a vertical plane on a pivot 19, and rotate on an axis 45 18'.

The lower end of the shaft 16 extends through a slot 20 in the floor 11 so as to allow the swinging movement above set forth. In order to prevent escape of the grain through the slot 20, there is mounted on the shaft a plate 21 which operates in a recess 22 in the floor.

The jaw 17 is normally held in a clamping position by means of a contractile coiled

spring 23 which is secured to the car frame, 55 the shaft being extended below the floor. There is mounted on the shaft 16 a lever 24 having connection with the spring 23 and provided with a pivoted handle 50, pivotally mounted as at 25, so that it may be 60 swung downwardly, out of the way. A similar lever 26 is slotted as at 51 and is slidably mounted on the shaft 16 and is intermediately fulcrumed on the car as shown at 27, the inner end of the lever being connected to a contractile coiled spring 28 anchored to the car frame, so that the shaft 16 may be shifted in the slot 20. By means of the lever 24, the shaft 16 may be rotated the jaw 17 being moved out of clamping 70 position with respect to the door boards 15, and the lever 26 has a handle portion 52 to swing downwardly like the handle 50 of the lever 24. The lever 26 is for the purpose of swinging the shaft 16 to cause the boards 15 to clear the edge of one of the posts 14 so that the grain pressing against the boards from the inside will press one end of the boards out and so release the grain. When the jaw 17 is pressed against the boards 15, 80 the handles of the levers can be moved downwardly to vertical positions at the edge of the car and held by pins 29.

At the opposite side of the door opening there is arranged a crank shaft 30 having its 85 ends 31 and 32 mounted to rotate in the top and the floor of the car respectively. To the lower end of the shaft 30 there is attached an arm 33 which by means of a spring 34, connected thereto and to the floor of the car, 90 holds the offset portion of the shaft 30 in engagement with the adjacent ends of the boards 15. The shaft 30 rotates and releases the boards at one end, when the other end of the boards swing outwardly through 95 the doorway as hereinbefore described.

Having thus described the invention, what is claimed is:

1. A grain door holder comprising a shaft having an offset jaw; means for mounting 100 the shaft at its upper end for axial rotation and for swinging movement in a vertical plane; spring means for rotating the shaft in one direction; means under the control of an operator for rotating the shaft in an 105 opposite direction; and means for imparting swinging movement to the shaft.

2. A grain door holder comprising a shaft

having an offset jaw; means for mounting the shaft at its upper end for axial rotation and for swinging movement in a vertical plane; a lever and a fulcrum therefor, the 5 lever being engaged with the shaft and constituting means for swinging the shaft; and spring means for rotating the shaft.

In testimony that I claim the foregoing as my own, I have hereto affixed my signature in the presence of two witnesses.

JOSEPH AMY AXT.

Witnesses:

EDWARD RUE,
W. H. SMITH.
